Patented Feb. 7, 1922.

UNITED STATES PATENT OFFICE.

JOSEPH M. ATKINSON, OF BALTIMORE, MARYLAND, ASSIGNOR TO OPPENHEIM, OBERNDORF & CO., INC., OF BALTIMORE, MARYLAND, A CORPORATION OF MARYLAND.

COMBINATION GARMENT.

1,405,962.

Specification of Letters Patent.

Patented Feb. 7, 1922.

Application filed April 2, 1919. Serial No. 286,856.

To all whom it may concern:

Be it known that I, JOSEPH M. ATKINSON, a citizen of the United States, residing at Baltimore, in the State of Maryland, have invented certain new and useful Improvements in Combination Garments, of which the following is a specification.

This invention relates to an improved combination garment designed especially for wear by children.

Garments of this character are subjected to hard usage and strains when worn, not only because of the activities of the normal child but also because garments of this character are usually designed to support certain of the outer garments, such as the trousers and stockings, and during play, the movements of the child produce considerable strains on parts of the garment.

The object therefore of the present invention is to provide an improved construction of garment for children which will meet the requirements.

The invention is illustrated in the accompanying drawing wherein,—

Fig. 1, shows the garment in front view.

Fig. 2, illustrates the same in rear view.

Fig. 3, shows a portion of the rear of the garment with the drop seat lowered, and

Fig. 4, illustrates an enlarged vertical section through the back of the garment as the same would appear if cut on the line 4—4 of Fig. 2.

Referring to the drawing the numeral 5, designates one front part of the garment and 6 the other front part thereof.

These two front parts are each preferably formed of a single piece of material which extends from the shoulder all the way to the lower edge of the leg,—the two parts being detachably connected by a central placket 7, which extends from the neck-opening 8, to the closed crotch 9.

At the rear, the garment has an upper back part 10, which has the usual cut-outs 11 and 12 at the neck and shoulders to coact with somewhat similar cut-outs in the front parts, to produce neck and arm openings. This back part 10 is united to the front parts by vertical side seams 13.

A reinforcing band 14, extends entirely around the garment from one edge of the placket 7, to the opposite edge thereof.

Vertical stay and reinforcing straps 15, are also stitched to the garment and extend

continuously from the band, 14, at the front up over the shoulder and down the back, terminating at said band 14, at the rear of the garment. As the band 14, at the rear of the garment is elevated with respect to the extreme lower edge 16, of the back part 10, the stay straps 15, also stop short of said back-edge, as clearly shown in Fig. 3, of the drawing.

I also prefer to secure a central stay strap 17, at the rear or back part 10, which strap extends vertically from the band 14, up to the neck opening 11.

At the point of joinder between each stay strap 15 and 17, and the band 14, I secure suitable fastening devices 18, such as buttons for the purpose of securing skirts or trousers from the waistband 14. These buttons are each strung on a tape 19, and the tape is inserted between the upper edge of the encircling band 14, and the lower end of a stay strap 15 or 17, as the case may be, so that any strain on the button will exert a downward pull on the upper edge of the band 14.

I also provide buttons 20, on the band 14, below the ends of the stay straps, for a purpose that will presently be explained.

By reference to Figs. 3 and 4, it will be noted that the back part 10, below the band 14, has its opposite edges secured in the side seams 13, and that the lower edge 16, of said back part, instead of being straight from side to side is arched in a cross-wise direction, being higher at the center than at the side seams.

This construction provides a more comfortable garment when the wearer is in a stooping or sitting position.

The seat and rear leg-portions of the garment, in the present instance, is formed of two parts or pieces of inelastic fabric 21 and 22, respectively which latter are secured to the front parts 6 and 5, by means of an inseam 23, and a short side seam 24.

In the present instance the short lower side seams 24, do not extend as far up the sides as the lower edge of the back part 10, but the seat portions 21 and 22, extend upwardly a considerably greater distance, whereby to completely overlap the lower portion of the back part 10. The free part of the seat and leg portions therefor form a part of a drop-seat flap 25.

To the upper edge of the drop seat flap 110

I secure a cross-wise strip 26, of elastic webbing which strip extends from one free side-edge of the seat-flap to the opposite free side-edge of the same, as clearly shown 5 in Fig. 2, of the drawing.

Across the upper edge of the elastic strip 26, I secure a double-thick inelastic strip 27 which extends throughout the length of the elastic strip and is provided with a plurality of button-holes 28.

Both the elastic and the inelastic strips 26 and 27, are therefore permanently secured to and form a part of the drop seat-flap.

15 At the opposite free side-edges I provide an inelastic strip 29, which extends from the extreme free edge 30, of the seat flap to the lower edge of the upper back part, as shown in Fig. 3, whereby to render the 20 seat-flap inelastic at its extreme side edges.

The seat and rear leg portions 21 and 22 of the garment are provided with a reinforce 31, which latter has its lower edges terminating at and secured in the inseam 25 23, and its upper edge terminating at the lower edge of the cross-wise elastic strip 26.

At the front of the garment I provide a tab 32, on each front part 5 and 6, which tabs are secured in the seam that holds the 30 reinforcing band 14, in place. The purpose of these tabs is for the attachment of stocking supports. These two tabs 32, are secured in the reinforcement or band 14, adjacent to the lower ends of the stay straps 35 15, so that the strains placed on the tabs will be transmitted to and be taken up by said straps 15, which extend from the front across the shoulders and down the back.

The strains applied to the seat and the 40 seat flap are taken up by the elastic insert strip 26, which is interposed between the seat and the flap fastenings 20, and by this means the liability of tearing away of those fastenings is reduced to a minimum.

45 Having described my invention, what I claim is,—

1. A child's undergarment comprising a waist and drawers, the drawers having side seams and also having a drop-seat that extends across the rear from one side seam to the other, an elastic strip having its lower horizontal edge secured to the upper edge

of the drop-seat, an inelastic strip secured to the upper horizontal edge of said elastic strip, securing devices to connect the inelastic strip to the waist and inelastic strips on the opposite vertical edges of the drop-seat which latter strips cross the ends of the elastic strip and render said ends inelastic and said latter inelastic strips being extended from the drop-seat and secured over the side seams. 55 60

2. An undergarment for children comprising a waist and drawers with a band extending across the waist at the front and back,—the drawers having side seams and side plackets and also provided with a drop seat which extends from one side placket to the other, an elastic strip having its lower edge secured along the upper edge of the drop seat between said side plackets, an inelastic strip having its lower edge secured along the upper edge of the elastic strip said inelastic strip when the flap is raised registering with the band that 75 extends across the back of the waist, and means for detachably connecting the inelastic strip of the drop-seat with the said band on the back of the waist whereby the elastic strip will pull directly on the inelastic strip which holds the drop-seat up. 80

3. An undergarment for children comprising a waist and drawers which are open down the front and are provided at each side with a placket which extends downwardly into the drawers,—the drawers of the garment having an inelastic drop seat portion between the side plackets with an inelastic strip across the upper edge, an elastic cross-strip having its upper edge 90 directly attached to the lower edge of the inelastic strip and its lower edge attached to the inelastic part of the drop-seat and the drop-seat being provided with a central rear strip whose upper edge terminates at 95 the lower edge of the elastic strip whereby the strain on the drop-seat will be directly applied to the lower edge of the elastic cross-strip and through the latter to the inelastic strip, and fastening means to detachably connect the inelastic strip to the waist above the drop-seat. 100

In testimony whereof I affix my signature.

JOSEPH M. ATKINSON.
